(57) **CLAIM**

The ornamental design for a packaging container having surface ornamentation, as shown and described.

DESCRIPTION

The patent or application contains at least one drawing executed in color. Copies of this patent or patent application with color drawing(s) will be provided by the Office upon request and payment of the necessary fee.

FIG. 1 is a front elevation view of a packaging container having surface ornamentation showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is an enlarged front elevation view of FIG. 1.

The broken lines of uneven length define the boundary of the claimed design and form no part of the claimed design. The broken lines of even length show unclaimed portions of the packaging container having surface ornamentation and form no part of the claimed design.
